UNITED STATES PATENT OFFICE.

EDWARD PATRICK BURNS, OF NEW BRITAIN, CONNECTICUT, ASSIGNOR, BY MESNE ASSIGNMENTS, TO THE BEATON & CADWELL MANUFACTURING COMPANY, OF NEW BRITAIN, CONNECTICUT, A CORPORATION.

FLUSH VALVE.

Application filed January 30, 1923. Serial No. 615,831.

To all whom it may concern:

Be it known that I, EDWARD PATRICK BURNS, a citizen of the United States, residing at New Britain, in the county of 5 Hartford and State of Connecticut, have invented certain new and useful Improvements in Flush Valves, of which the following is a specification.

My invention relates to improvements in 10 flush valves of the form that is shown in applications filed by myself April 12, 1921, Serial No. 460,794, and October 29, 1921, Serial No. 511,301, and the object of my improvement is to incorporate in a flush 15 valve structure that in its operative features corresponds closely to the device shown and described in application Serial No. 511,301 mentioned above as to certain details in the structural features, particularly as applied 20 to the air chamber and operating button or knob, whereby there is attained in the construction an advantageous result in the way of simplicity and economy and without impairment of the convenience and efficiency 25 in use.

In the accompanying drawing:

Figure 1 is a side elevation of my improved flush valve.

Figure 2 is a plan view of the same.

Figure 3 is a plan view with the casing cover part removed.

Figure 4 is a sectional view on an enlarged scale on the line 4-4 of Fig. 2.

Figure 5 is a plan view of the main valve 35 structure and adjacent parts.

Figure 6 is a side elevation of the auxiliary valve structure and the operating button or knob and the adjacent parts.

My improved flush valve is based upon 40 the structure that is shown and described in application Serial No. 511,301, and comprises a generally pear-shaped casing structure having the water inlet 10 at one side, having at the lower end a downwardly extending nipple 11 that is exteriorly screw-threaded for connecting with the outlet pipe 12, and being provided at the upper end 45 with the button or knob 13 that serves as the tripping means or operating means by being adapted to be depressed to operate the valve.

Said button 13 is restored to the normal elevated position automatically through the operation of the mechanism that is housed

within the casing and which mechanism may include a spring 14.

55

Structurally said casing structure comprises for the exterior a casing cover part 15 at the upper end, a base part 16 at the lower end, and the casing body part 17 intermediate said first mentioned parts, co-operating screw-threaded portions 18 of suitable form serving as the means of interconnecting said parts.

60

The inlet connection 10 is made integral with the casing body part 17 and the nipple 65 11 for connecting with the outlet pipe 12 is made integral with the base part 16.

65

As a part of the fixed casing structure there is provided in the interior a part that is designated as the water chamber top 19 70 that is positioned on the upper side of the body part 17 and is secured thereto by means of a flange-like annular border portion 20 through the medium of the screws 21. Said annular border portion 20 serves as a seat, 75 is opposed to a similar seat 22 on the body part 17, and interposed between said seats 20 and 22 is the edge portion of a circular diaphragm 23, which may be made of any suitable material, such as metal or rubber. 80

80

The diaphragm 23 bridges generally the upper portion of the body part 17 and serves as the top wall of the main valve chamber 24, the latter being connected with the inlet 10.

85

The main valve 25 is fixedly connected with the middle portion of the diaphragm 23, on the lower face thereof, and is raised and lowered relatively to the valve seat 26 to correspond to the movements of said diaphragm.

90

The casing body part 17 extends generally across the lower side of the valve chamber 24 so as to provide the fixed, lower wall 27 thereof, which wall 27 is of annular form, 95 extending around the main valve seat 26.

95

Extending downwardly from the valve seat 26 and supported by said annular wall 27, is the tubular structure 28 that encloses the main discharge passage 29.

100

Said tubular structure 28, it will be noted, extends through the nipple 11 and terminates appreciably below the lower end thereof; is separated from the opposed border wall of said nipple 11 by an annular space 105 30; and is generally in the form of a nozzle

or jet, after the manner of an injector, with the lower end portion 31 of the discharge passage 29 appreciably smaller in diameter than the upper end portion 32, adjacent the 5 valve seat 26.

The annular space 30 mentioned serves as the discharge passage or drain passage for the drainage chamber 33 that is provided on the lower side of the annular wall 10 27, being intermediate said annular wall 27 and the casing base part 16.

On the upper side of the diaphragm 23 and between the same and the general structure of the water chamber top 19 is the 15 water chamber 34.

Said water chamber top 19 comprises just inside the border and seat portion 20 a curved, dome-shaped portion 35 that extends generally inwardly and upwardly from 20 said seat portion 20 and is surmounted by the axially positioned tubular structure 36.

The tubular structure 36 comprises a lower portion 37 of relatively large diameter, an inwardly directed end wall 38 at 25 the upper end of said lower portion 37, and an upper portion 39 of appreciably smaller diameter extending upwardly from said end wall 38.

The lower portion 37 is of uniform diameter 30 and operates as a cylinder for the piston-like stem 40 of the main valve 25, which stem is fluted or corrugated so as to provide longitudinal passages 41 for water.

The upper and major portion of the 35 upper portion 39 has a bore that is an operative fit for the rod 42 that serves as the valve stem for the auxiliary valve 43. The bore 44 at the lower end of said upper portion 39 is slightly enlarged, so as to provide clearance for the rod 42 for water and the side wall of said enlarged portion or bore 44 is provided with a plurality of perforations 45 for the escape of water.

The corner 46 at the junction of the upper 45 portion 39 and the end wall 38 serves as a seat for said auxiliary valve 43.

The auxiliary valve 43, as described, is operative to control the outflow of water from the water chamber 34.

50 The piston-like stem 40 is provided with a laterally extending flange adjacent the lower end so as to provide a relatively large head 47 for being seated on the diaphragm 23 and is extended downwardly 55 axially in the form of a threaded nipple 48 for receiving the nut 49, the main valve 25 being interposed between said head 47 and nut 48.

The main valve 25 may be provided with 60 a contacting washer 50 of yielding material for cooperating with the valve seat 26.

The auxiliary valve 43 is also provided with a contacting washer 51 of yielding material.

65 The upper end of the piston-like stem 40

is chambered, as shown at 52, to house the lower end portion of the auxiliary valve 43 when the main valve 25 and connected parts are in the extreme upper position.

The water chamber 34 is connected at all 70 times with the water supply by means of a restricted passage in any proper manner, the means for effecting such connection in the present instance being provided by means of a small tube 53 that is housed in 75 a suitable continuous perforation 54 in superimposed portions of the head 47, diaphragm 23, and main valve 25.

The piston-like stem 40 has an axial bore 55 that is open at the upper end and serves 80 as a spring chamber for housing the spring 14, which spring is of coil form.

The upper and major portion of the spring 14 encloses a spring guide 56 that extends 85 downwardly from the auxiliary valve 43 and that also serves after the manner of a nut as the means for holding said valve 43 on the rod or stem 42, the upper end portion 57 being longitudinally bored and screw-threaded to cooperate with the threaded 90 lower end portion 58 of said rod or stem 42. A diminutive shoulder 59 on said rod 42 limits the upward movement or position of the valve 43 along said rod 42.

The stem or rod 42 projects upwardly 95 above its adjacent supporting structure that is provided by the tubular structure 36, said adjacent supporting structure consisting of the part that is designated as the upper portion 39. Said upper portion 39 is of tubular, sleeve-like form, is of appreciable length so as to be adapted to operate efficiently 100 as a guide for the rod 42, and has the perforations or vent openings 45 in the side wall, as mentioned. Said rod 42 operates 105 freely in said sleeve-like upper portion 39, the structure being free from any form of stuffing box. Thus under conditions of use water will be ejected through the vent openings 45 and some will pass along the rod 110 42. Means were provided in the previous structure for diverting such water away from the opening in the casing cover part 15 for the operating handle in the form of a water-shed device or umbrella. In the 115 present instance means for effecting the same result are provided of different form, as will be described.

In the present instance, the upper end portion 60 of the rod 42 projects only 120 slightly above the adjacent supporting portion 39, the amount being sufficient to provide for the slight movement required for the rod 42 and some extra for clearance. The water-shed or umbrella 61 is the form 125 of a metallic cup, positioned in inverted form, and mounted on the end of the rod 42, the side wall extending downwardly over the vent openings 45, and which constitutes the body structure of the handle or 130

button 13. A boss 62 on the cover part 15 has an opening 64 that is an operative fit for the side wall 63 of the umbrella or body 61. A contact button serves as the handle or button proper 13, being mounted on the end wall 65 of the body 61, and this part may be made of porcelain and marked with the word PUSH or some other suitable inscription.

10 The casing cover part 15 is dome-shaped and provides an air chamber 66 immediately exterior to the water chamber 34 and which is operative to receive the water that is ejected from said water chamber 34 in 15 the manner already explained.

One or more perforations 67 may be provided in the side wall of the casing cover part 15 to admit air and maintain atmospheric pressure in the interior.

20 In order to drain water that may be admitted to the air chamber 66 one or more connecting passages 68 are provided leading to the drain chamber 33. As shown, said passages alternate with the holding screws 21 and are in the form of continuous openings that pass through the material of the flange 20 of the water chamber top 19, the diaphragm 23, and the solid material 69 at the border of the casing body part 17.

30 In use, the drainage of the air chamber 66 is accelerated by the aspirator effect produced by the discharge from the main discharge passage 29, which is relatively restricted, as described, and terminates slightly below the adjacent and concentric discharge outlet 30 for the drain chamber 33.

In use, the main valve 25 and the auxiliary valve 43 are normally closed; water is admitted to the valve chamber 24 below 40 the diaphragm 23 and exterior to the valve seat 26 and the discharge passage 29; the water chamber 34 is filled with water, the water being retained therein by the auxiliary valve 43; and the air chamber 66 is 45 in the drained condition.

The spring 14 tends to hold both valves in the closed position and the water pressure also cooperates to effect this result.

To operate the device the button 13 is 50 depressed, so as to unseat the auxiliary valve, the operation of the handle or button being momentary only. Thus the water chamber 34 is relieved of pressure, the water therein is ejected through the perforations 55 45. The water on the lower side of the dia-

phragm lifts the same and carries with a the main valve. At the same time the auxiliary valve 43 is seated so that further escape of water from the water chamber 34 60 is prevented. This condition is followed by the re-filling of the water chamber 34 from the water supply through the restricted passage that is provided by the diminutive connecting tube 53.

65 The dimensions of said tube 53 determine

the rate of such filling of the water chamber 34 and the period of time for the flow of water for flushing, as such filling is accompanied by a reverse movement of the diaphragm which is terminated by a seating of the main valve on the main valve seat. 70

The umbrella or body 61 has at the lower end of its cylindrical side wall 63 an outwardly flaring umbrella-like enlargement 68 that serves to divert water from the interior 75 laterally and also operates as a stop to prevent the removal of the knob or handle structure 13 while the casing parts are in the usual assembled position by limiting the upward movement thereof. Said enlargement in its uppermost position engages 80 with the lower end portion of the border wall for the opening 64 in the boss 62.

I claim as my invention:—

1. In a flush valve, an inner casing part 85 having an upper portion that is provided with a pilot opening, a pilot valve housed within said casing part, a stem projected upwardly from said valve, through said upper portion, and having a free end portion that extends above said upper portion, said stem comprising an elongated body portion and said upper portion having guide means for cooperating with said body portion, a button-tripping member mounted on 90 said free end portion of the stem, and means that are operatively free from said stem for guiding said button-tripping member. 95

2. In a flush valve, a casing comprising an interior structure that is divided by a 100 diaphragm so as to provide a water chamber on the upper side thereof and a cover part enclosing said water chamber, the wall of said water chamber having a pilot opening, an auxiliary valve for said opening 105 having a stem that projects upwardly through said wall, said cover part having a guide opening in alignment with said stem, a button-tripping member and said member being loosely mounted directly on the 110 upper end of said stem and guided for free movement in said guide opening and said member having a wall structure that extends downwardly over said pilot opening and in spaced relation thereto. 115

3. In a flush valve as described in claim 2, the extreme lower end portion of said wall structure being flared to a larger diameter than the border wall of said guide opening. 120

4. In a flush valve, a casing having a pilot opening, a valve for said opening having an upwardly directed stem, a cover having an opening in registration with said stem, a button-tripping member mounted on said stem, means for guiding said stem, other means for guiding said member, and the mounting of said member on the stem being such as to permit of limited relative lateral movement thereof. 125 130

5. In a flush valve, an interior casing structure having a pilot opening adjacent the upper end, an exterior casing structure surmounting said interior casing structure and having an opening for a tripping device at the upper end portion, a pilot valve having a stem that is projected upwardly into said last named opening, means for guiding said stem, and a tripping device, said tripping device being in the form of a cup-like structure that is guided for free movement in said last named opening and that is loosely mounted on the tip end of said stem.
10. In a flush valve, a casing having a water chamber that is provided with a top wall, said top wall having a pilot opening, a valve for said opening having an upwardly directed stem, and said top wall having an upwardly directed tubular por-
- tion that is in contact with and serves as 20 a guide for said stem.
7. In a flush valve a casing comprising an interior portion, mechanism housed generally within said interior portion and comprising a stem for a pilot valve that projects upwardly through the enclosing wall, a cover exterior to the upper portion of said interior portion, said cover having an opening in registration with said stem, a button-tripping member mounted on said 25 stem and operatively housed in the opening in said cover, and said button-tripping member being in the form of a one-piece structure of cup-like form that is admitted to said opening in the cover from the inside 30 thereof.
15. In a flush valve, a casing having a
